TOP ROLLS FOR SPINNING FRAMES

Louis M. Cochett, Whitman, Mass., assignor, by mesne assignments, to Machinecraft, Inc., Whitman, Mass., a corporation of Massachusetts

Filed Apr. 15, 1957, Ser. No. 652,766

10 Claims. (Cl. 19—142)

The present is an improvement on the top roll of my Patent No. 2,771,640.

This invention relates to top rolls for spinning and roving frames, and has as its object the provision of a novel and improved shell type top roll especially suited for use in frames in which the top rolls are mounted without the use of cap bars, but instead are held in working relation with the bottom rolls by guides which engage solely with the necks between the bosses or roll shells of the top rolls. Such guides also apply the weighting force to the rolls and thus also perform the function of the saddles used heretofore. As in the above patent, the present roll is of the type in which the two bosses of the top roll are mounted on a common live shaft which rotates in unison with the bosses. A sleeve on which the hollow bosses or roll shells are rotatably mounted by means of anti-friction bearings is provided about the shaft for engagement by the guiding and weighting means aforesaid to hold the top roll in its working position. Since the sleeve engaged by the guiding and weighting means remains stationary no lubrication is needed and no wear occurs at the points of such engagement, and the bearing surfaces are wholly within and shielded by the roll shells.

An important advantage of this type of top roll over the prior types of ball-bearing top rolls is that because the bosses or roll shells are fixed on the ends of the shaft one end of each boss or shell is by nature closed against access of lint, fly, and dirt to the ball bearings and likewise against egress of lubricant from the bearings as well as entry of air to oxidise the lubricant. Hence only one end of each boss or shell is exposed to invasion by lint and needs to be protected by the lint seal which forms an essential adjunct of every commercially useful top roll using anti-friction bearings.

In my prior patent the bosses have been fixed on the ends of the shaft by staking through a radial hole in each boss, to raise a rim of the shaft metal into such hole and thus key the boss to the shaft. Alternatively, the bosses have been screwed tightly onto the threaded ends of the shaft, as in my Patent No. 2,937,414. In the first of such constructions, the bearing tension is set by hand before the staking operation; in the second it is determined by the accuracy with which the parts are formed in machining. In either case there is no simple and easy way of readjusting the bearings to correct an initial incorrect adjustment of the bearings or to take up slack therein after prolonged use and resulting wear.

Hence, a leading object of the present invention is to provide for such adjustment of the bearing tension in a live-axle ball bearing top roll, and further to make such adjustment automatic.

To this end, the roll shells forming the bosses are mounted on the axle in operatively fixed but axially slideable relation, and are yieldingly urged in the direction to take up slack in the angular-contact ball bearings by constantly acting resilient means compressed between the end-caps and the ends of the bosses adjacent thereto. Thus errors in machining or assembling are corrected, and any eventual wear in the bearings is compensated for.

Other aims of the invention are to simplify the construction and assembly of the top roll with attendant saving in cost of production, and to increase the weight-

2

carrying capacity of its anti-friction bearings with resulting longer useful life, as well as to maintain precise coaxial relation of the bosses to the axle and to each other so as to prevent any tilting of the bosses as they rotate.

The manner of attainment of these and other features of improvement is as set forth hereinafter.

An illustrative embodiment of the invention is shown in the accompanying drawings, in which—

10 Fig. 1 is a side elevation of the improved roll.

Fig. 2 is an end view of the same.

15 Fig. 3 is a section on an enlarged scale, taken on line 3—3 of Fig. 1.

The present top roll is especially suited for use as the 20 apron roll in my improved apron guide set forth in my Patent No. 2,943,361.

The novel roll comprises an axle 1 of commercial 25 cold rolled steel round stock having at each end a reduced and threaded extremity 3 and an adjacent radial shoulder 5. Surrounding the axle 1 is a stiff steel sleeve 7 having an internal diameter materially larger than the diameter of axle 1, and slightly less in length than the latter. Each end portion 9 of this sleeve is reduced in outside diameter and provided with circumferential grooves 11 at spaced points in its length to form the inner races or cones for the balls 13 of the ball bearings. Bearing balls 13 are mounted in cages 15 as customary for unit handling.

30 The two bosses or roll shells 17 are knurled exteriorly and each has a portion 19 of large internal diameter closely fitting over the balls 13 positioned in the grooves 11, and a short small diameter passage 21 fitting closely but slidably on the cylindrical outer surface of an end cap 23 internally threaded and screwed onto the end portion 3 of the axle 1 to seat tightly against shoulder 5.

35 The outer set of balls 13 runs in the ball race 25 formed by the junction of the cylindrical interior wall of large diameter portion 19 with the transition surface 27 running to the small diameter passage 21. The ball race 25 may be either curved to the radius of the balls 13, as shown, or made angular by forming the surface 27 either as a straight taper or radial, as may be preferred. Thus the outer set of balls 13 form an angular-contact ball bearing capable of taking both the radial load of modern heavy roll-weighting practice, and the very material 40 end-thrust resulting therefrom when the top rolls digress from exact parallel relation to their opposing bottom rolls.

45 The inner set of balls 13 holds the inward portion of the boss or roll shell 17 in concentric relation to the sleeve 7 under radial loads, shares the radial load, cooperates with the outer set to hold the bosses in coaxial relation to each other, and prevents any tilting of the boss about the outer ball set which might be permitted by the free fit at passage 21.

50 Each boss 17 is held in working position by one or more resilient annular members or washers 29 surrounding the shank of end cap 23 and confined between the flange 31 of its head and the radially extending bottom 33 of a counterbore 35 formed in the outer end of the

55 boss for the reception of such washers. These washers connect the bosses to the axle by frictional engagement and cause these parts to rotate in unison when the bosses are revolved. Preferably these washers 29 are made of neoprene or other oil-resistant rubber compound, though they may be made of felt if desired. They are put under compression when the end caps 23 are screwed down tight against shoulders 5. Thus they react against the surface 33 of the counterbore to slide the boss inward along the surface of the end cap 23 which forms in effect a continuation of the axle 1, until the outer set of balls 13 is seated in ball race 25 with the desired bearing ten-

sion. These angular ball bearings thus fix the limit of movement of the bosses inwardly along the sleeve. In this way, by choice of the proper thickness and yieldability of the washers 29, the tension of the outer ball bearing of each boss is automatically adjusted in the act of assembling the roll and thereafter remain self-adjusting to compensate for wear of this ball bearing. This is because the resilient washers continuously urge the bosses inwardly along shaft 1 and its continuation formed by the shanks of the end caps and over the sleeve 7.

The bore of each boss or roll shell 17 is completely closed at its outer end by the head of the end cap 23 and the elastic washers 29 against entry of lint and fly and escape of lubricant from the ball bearings.

Sealing of the other end of the boss against entry of lint and other foreign matter is necessary to prevent fouling the bearings, lest the uniform rotation of the bosses be checked with resulting uneven drafting of the strand. This is accomplished by a lint seal 37 in the form of a collar 39 seated in a groove 41 formed in the full-diameter part of sleeve 7 just inward of the reduced portion 9 thereof. This collar is made of nylon or other suitable resilient synthetic plastic material, and has a concave or mushroom shaped flange 43 which tapers in thickness toward its rim. Its diameter across the rim initially slightly exceeds that of the large diameter portion 19 of the interior of the boss. Thus when the bosses are installed on the sleeve 7 the flange 43 remains continuously in wiping contact with the rotating bosses just inside the mouth of the portion 19. It thereby blocks the access of lint and other matter, and also serves to prevent the escape of lubricant from within the bosses.

Each end cap 23 is provided with means for screwing it onto the ends of the axle, and for easily unscrewing it to disassemble the roll for cleaning or repair. This comprises an axial bore 45 provided with radial slots 47 for engagement by a screw driver.

Each boss has its outer end beveled at 49 for engagement by the centers of a buffing machine used for trueing the cots adhesively applied to the bosses, when cots are used on the roll.

The shallow grooves 51 in sleeve 7 are engaged by the saddle element to hold the top roll against endwise shift of its position in the frame.

It is to be noted that the end caps are recessed into the bosses flush with the ends of the latter. Thus there is nothing projecting beyond the boss ends to catch the yarn and impede its insertion between the top and bottom rolls of a pair as the spinner pieces up a broken end of yarn by entering it obliquely beneath and behind the boss, in the simplified manner of "side-piecing" which forms a main feature of the capbar-less spinning frame. Also, the bevel 49 sheds any yarn which might encounter it in performing this operation.

The use of end caps with female threads screwed onto the axle ends facilitates the making of these parts by automatic screw machines. It is easier and cheaper to bore and tap the end caps than to do this to the axle ends to admit retaining screws.

While I have illustrated and described a certain form in which the invention may be embodied, I am aware that many modifications may be made therein by any person skilled in the art, without departing from the scope of the invention as expressed in the claims. Therefore, I do not wish to be limited to the particular form shown, or to the details of construction thereof, but

What I do claim is:

1. A top roll having in combination an axle, a sleeve around the axle, bosses operatively fixed but axially slideable with respect to the axle, two sets of ball bearings spaced apart from each other lengthwise of each boss and located between each boss and the sleeve supporting the bosses rotatably and holding them in coaxial relation to each other, and means urging the bosses inwardly of the axle.

2. A top roll having in combination an axle, a sleeve around the axle, bosses axially slideable along the axle, two spaced sets of ball bearings between each of the bosses and the sleeve supporting the bosses rotatably and holding them in coaxial relation to each other, and means frictionally engaging the bosses causing these parts and the axle to rotate in unison.

3. The combination according to claim 2 in which the said means yieldingly urge the bosses inwardly of the axle.

10 4. A top roll having in combination an axle, a sleeve around the axle, bosses axially slideable with respect to the axle, angular contact ball bearings between and engaging with the bosses and the sleeve, radial contact ball bearings located between the bosses and the sleeve inwardly of the angular contact ball bearings and preventing tilting of the bosses, and means yieldingly urging the bosses axially of the axle.

20 5. A top roll having in combination an axle, a sleeve around the axle, bosses, angular contact ball bearings and radial contact ball bearings between and engaging with the bosses the sleeve, and end caps on the axle, and neoprene rings pressed against the bosses by the end caps and establishing the bearing tension of the ball bearings.

25 6. A top roll having in combination an axle, a sleeve around the axle, bosses, angular contact ball bearings and radial contact ball bearings between and engaging with the bosses and the sleeve, end caps on the axle, and resilient frictional means between the end caps and the bosses 30 urging the latter axially of the sleeve and causing the bosses and axle to turn in unison.

7. A top roll having in combination an axle, a sleeve about the axle, end caps on the axle having flanges, bosses each having a passage fitting slidably on an end cap inwardly of its flange and a portion of larger internal diameter extending over the sleeve, angular contact ball bearings and radial contact ball bearings between the bosses and the sleeve holding the bosses in coaxial relation, and resilient washers between the flanges of the end caps and 35 the surfaces of the bosses adjacent the said passages, such washers being put under compression by the flanges and reacting against the bosses to establish the bearing tension of the angular contact ball bearings.

8. A top roll having in combination, bosses, a sleeve, ball bearings engaging the sleeve and each boss at two 45 points in its length and supporting the bosses rotatably in coaxial relation, and means including an axle and removable flanged terminal members extending through the sleeve and holding the bosses on the end portions of the sleeve.

50 9. The combination according to claim 8 in which angular contact ball bearings fix the limit of movement of the bosses inwardly along the sleeve, and resilient elements in connection with the means extending through the sleeve urge the bosses inwardly to adjust the tension 55 of such bearings.

10. A top roll having in combination an axle having screw threaded ends, a sleeve surrounding the axle, bosses, two sets of ball bearings between each of the bosses and the sleeve holding the bosses in coaxial relation, end caps screwed onto the ends of the axle as far as the screw threads will permit, and resilient non-metallic annular members interposed between the end caps and the bosses and put under compression by the end caps and establishing the bearing tension of the ball bearings.
